COOKING RANGE

Harrison K. Linger, Wheaton, Ill., assignor to General Electric Company, a corporation of New York

Filed Sept. 11, 1961, Ser. No. 66,675

Term of patent 3½ years

(Cl. D81—4)

FIG. 1 is a front perspective view of a cooking range showing my new design, with a fragmentary broken line showing of a counter for purposes of illustration;

FIG. 2 is a side elevational view; and

FIG. 3 is a partial section viewed along line 3—3 of FIG. 1.

The undisclosed side of the range is substantially the same as the side shown and the rear is substantially plain.

I claim:

The ornamental design for a cooking range, substantially as shown and described.
